UNITED STATES PATENT OFFICE.

JULIUS BRENZINGER, OF FAIRFIELD, CONNECTICUT, ASSIGNOR TO THE MAX AMS MACHINE COMPANY, OF NEW YORK, N. Y., A CORPORATION OF NEW YORK.

CAN-BODY-FORMING MACHINE.

Application filed December 20, 1919. Serial No. 346,366.

To all whom it may concern:

Be it known that I, JULIUS BRENZINGER, a citizen of the United States, residing at Fairfield, in the county of Fairfield and 5 State of Connecticut, have invented certain new and useful Improvements in Can-Body-Forming Machines, of which the following is a specification.

This invention relates generally to machines for forming the body portions of sheet-metal containers, commonly known as 10 tin cans, from flat blanks. Such a machine is usually designed to form the first link in a chain of machines, wherein the work units 15 are delivered from each machine to the next in succession and which cooperate to form the can body, apply solder exteriorly to the side seam, flange the end edges of the formed body and double-seam one of the end portions thereto, whereupon the container is 20 ready for delivery to the packer for filling and sealing.

Obviously, all of the machines of such a chain must operate at a uniform rate of 25 speed, so far as output capacity is concerned. Recent rapid development of flanging and heading machines, however, may be said to have caused such machines to outstrip forming and soldering machines in possible 30 speed of practical and dependable operation, and efficiency demands that the maximum output capacity of flanging and heading machines be not curtailed on account of a lower maximum rate of deliveries of work units 35 thereto. It will be apparent, therefore, that a body forming machine, in spite of having to perform successively the various operations of notching, edging, bending, interlocking, compressing, fluxing, soldering, 40 wiping and cooling, should be capable of dependable operation at comparatively high speed.

Furthermore, it is well known that tin cans are made in many different standard 45 shapes and sizes. Modern flangers and double-seamers are, as a rule, capable of ready and comparatively simple adjustment to meet the requirements of a wide range of different standard sizes of parts to be operated upon; but the mechanisms of a forming machine, which must not only be adapted to successfully perform the operations above set forth but which must include means for effecting intermittent movement

of the blanks, in progressive stages of formation, in continuous procession from one operating station to the next and thus through the machine, are necessarily complex and more or less complicated. The cost of such a machine is doubtless far too great 55 to justify what may be termed the average can manufacturer in providing himself with a separate machine for each size of can desired to be produced; and not only that, but the economy effected through the adjustable 60 features of modern flangers and double-seamers would be utterly lost in case the forming machine were not also capable of like adjustment.

Furthermore, this same complexity and 65 complication necessarily leads to difficulties in connection with the repair or replacement of broken or worn parts, well known to be altogether too frequently occurring in the use of all metal-working machinery. Efficiency again demands the ready accessibility 70 of such parts, and that such accessibility be not gained at the expense of the requisite strength, rigidity, accuracy and general dependability of the machine. 80

Furthermore, the well-known difficulties attendant upon the handling of thin sheet-metal blanks, due to inherent malformations, irregularities, imperfections and the like, not infrequently result—even in the 85 most carefully designed and constructed machines—in failure of intended operations and consequent distortion and “jamming” of one or more of the work units, rendering clearance necessary before operations can 90 be continued. Therefore, the entire path of travel of the blank, in process of formation, should be capable of ready accessibility for purposes of removal of distorted and “jammed” blanks and requisite readjustment; and this requirement, obviously, involves the necessity for quick stoppage of the forming machine and preferably, as will be apparent, without stopping other machines in the chain—as, for instance, the 100 soldering machine, wherein premature cooling of an incompletely soldered can body would be likely to cause more trouble.

Furthermore, in endeavoring to construct a can-body forming machine capable of a 105 speed of operation equivalent to the maximum capacity of modern flanging and heading machines, quick operation of the notching

ing, edging, bending and compressing tools is really subordinate to quick removal of these tools from the path of travel of the blanks, so that the periods of rest may be 5 of the shortest possible duration.

Furthermore, the inertia or momentum of the advancing blanks must be taken into consideration. Each of these blanks must obviously be brought to an exactly-adjusted 10 position of rest in each of the various mechanisms, successively. To fall short of reaching such position would, of course, be fatal. To effect the reaching and retaining of such position by initial delivery is, of course, 15 a practical impossibility. Therefore, it is desirable—if not essential—that each blank be carried slightly beyond each proper position, and upon being released from its advancing means be returned to engagement 20 with suitable stops or gauges—and this in addition to the provision of means for partially overcoming or minimizing momentum.

Furthermore, the necessity of bringing the 25 advancing work units periodically into conditions of rest would naturally seem to render indispensable intermittently operating advancing means, the simplest and probably most satisfactory form of which is 30 that of one or more reciprocating parts or members. In such case, these parts are generally provided with pivotally mounted pusher-pawl spring-pressed to operative or engaging positions, whereby upon the return 35 or rearward stroke of the reciprocating parts the pawls will be depressed to clear—or otherwise withdrawn from the path of movement of—the positioned blank which has just been advanced. It is essential that 40 these pawls be sensitively responsive to depressing forces, particularly in a rapidly operating machine, in order to safeguard against breakage of the tools or distortion of the work and to minimize friction, and yet 45 be quickly, effectively and dependably returned to engaging positions as each positioned blank is cleared.

Furthermore, the edgewise and sidewise advancing blank must be first notched at 50 opposite ends thereof, then “edged” at these same ends, and then bent to form and the “edged” ends interhooked. While the notching punches, the “edging” tools and the bending means must obviously all be power- 55 fully and in a certain sense independently operated, operation of each particular set of instrumentalities must be synchronous and in certain cases cooperative, and this with the advancing mechanism interposed 60 between opposite members thereof. Not only does economy, as well as efficiency, demand again that the requisite strength and rigidity, essential to power and synchronism, be obtained without cumbersomeness, 65 but sight must not be lost of the necessity

for ready accessibility of both tools and work and facility of dimensional adjustment.

Furthermore, in view of the thinness and consequent flexibility of the metal sheets being operated upon, inherent imperfections and irregularities and the slight dimensional variations, it is desirable in many cases that the forces applied throughout the various operations be of a yielding character; in others 70 that the force-applying means be initially yielding and subsequently become or be made inflexible. For instance, it has been found best to hold the blank yieldingly against the forming mandrel during the bending opera- 75 tion, but after the edged ends have been interhooked all of the parts should be rigidly supported against the action of the seam-compressing die. 80

The principal object of the present invention is the provision of a machine which will to the greatest possible extent meet the requirements above set forth, and otherwise, in general, simplify and improve the construction and operation of present known 85 can-body forming machines, not only without sacrifice of efficiency and dependability but with actual and material advance in these qualities.

In the accompanying drawings, forming 95 a part of this specification, I have illustrated a machine which I believe to be the most practical and convenient embodiment of my invention. In these drawings:

Fig. 1 is a side elevation, partly in section, of the machine, showing what may be considered as the right side thereof: 100

Fig. 2 is a top plan view of the same:

Fig. 3 is a central, longitudinal, vertical section, taken substantially on the line 3—3 105 of Fig. 2;

Fig. 4 is an end view, looking from the right in Fig. 1;

Figs. 5, 6 and 7 are enlarged transverse sections, taken on the lines 5—5, 6—6 and 110 7—7, respectively, of Fig. 1;

Fig. 6^a is a partly sectional detail view of the righthand tool or die holder of the notching mechanism shown in Fig. 6.

Fig. 8 is an enlarged longitudinal section, taken substantially on the line 8—8 115 of Fig. 2, the parts being shown in what may be termed forward positions:

Fig. 9 is a transverse section taken substantially on the line 9—9 of Fig. 8: 120

Fig. 10 is a top plan view, partly broken away, showing the feed and stop pawls on the right-hand side of the machine:

Fig. 11 is a side elevation, partly in section, of Fig. 10; 125

Figs. 12 and 13 are enlarged transverse sections, taken on the lines 12—12 and 13—13, respectively, of Fig. 11;

Fig. 14 is an enlarged detail end view, differing from Fig. 4 in that the forming 130

or bending wings are shown in open positions;

Fig. 15 is a vertical section, taken substantially on the line 15—15 of Fig. 14;

6 Figs. 16, 17 and 18 are plan views and Fig. 19 an edge view of a blank, showing the results of the notching and edging operations, and

10 Figs. 20, 21 and 22 are sectional views through the mandrel illustrative of the effects of the compressing operation after interhooking of the edged ends of the blank.

The machine illustrated comprises a substantial base A upon which is mounted an 15 upright, inverted U-shaped frame B, and a horizontal bed C bolted to the frame B at its forward end and supported by the legs D at its other end, said legs being preferably integral therewith and suitably 20 secured to the base A. The bed C, in the form shown, is a substantially rectangular dish-shaped casting provided with interior lateral ribs c¹ and c², at least one of which (c¹) and the forward wall c³ are recessed 25 along their upper ends to provide guideways for lateral movement of the longitudinal bed-plates E and E', right and left of the middle line of the machine, respectively, whereby said bed-plates are laterally 30 adjustable with reference to each other. To effect such lateral adjustment, I have shown rods d¹ and d² passing through the side walls c⁴ and c⁵ of the bed C and threaded into lugs d³ and d⁴ depending from said 35 bed-plates E and E', respectively, the outer ends of said rods being squared for the reception of a wrench or crank whereby said rods may be readily turned and operate to move said bed-plates toward and from each 40 other.

As hereinbefore stated, the machine of the present invention is designed to receive, successively, flat and rectangular sheet-metal blanks and advance the same in continuous 45 procession therethrough, automatically notching, edging and forming each blank in transit, interhooking the edged ends and compressing the interhooked portions into a substantially solid seam. Perfect can bodies 50 cannot be produced unless the notches in each blank are positioned and dimensioned with the greatest accuracy, the edges turned with unerring uniformity and in such manner as to preserve substantially perfect 55 rectangularity, and the notched and edged blank delivered to the forming mechanism with its edged ends precisely paralleling the axis of the forming horn or mandrel. It will be apparent, therefore, that the first 60 and foremost requisite of a machine of this character is the provision of advancing means of such character as to insure processional movement of the blanks in perfect alignment. The slightest deflection of a 65 blank in transit would result, in the notching

mechanism, in displacement and improper dimensioning of two or more of the notches, in the edging mechanism in distorted hooks, and in the forming mechanism in failure of the hooked ends to properly 70 inter-engage. Obviously, to insure such alignment, the advancing forces must be applied at more than one point, and if the blank is pushed along by means engaging its rear edge—as is, so far as I am aware, 75 the invariable practice—two points of force-application are as good as a thousand, but these points should be as widely separated with reference to the blank-edge as practicable—particularly considering the adjustability of the machine for the manipulation of blanks of various standard sizes. This comparatively wide separation, in view 80 of the fact that the thin and flexible sheet must be supported between the points of application of the advancing forces, renders necessary the employment of what practically amount to two separate and independent advancing mechanisms. Obviously, however, these mechanisms must be so actuated, or so inter-connected as to insure absolute synchronism of movements—otherwise, perfect alignment would be an impossibility, even with the most carefully adjusted 85 guideways, unless fitted so snugly in the latter as to interfere with the essential freedom of movement thereof on account of friction—and it is to be remembered that under any conditions provisions must be made for the slight variations in the dimensions of blanks intended to be of uniform size. Furthermore, in endeavoring to insure retention of this essential alignment of the blanks in transit, consideration must be given to the hereinbefore-mentioned necessity, 90 for a slight over-throw of each blank and return of the same to proper position in each of the notching and edging mechanisms, and this in connection with the necessity for effecting ready access to the 95 path of travel of the blanks for the removal thereof in case of distortion due to imperfections and otherwise, in an emergency, as might be desirable or essential.

I do not claim for the advancing means 100 of the machine of the present invention any radical departure in general principles from mechanisms now well known and in common use; but I do claim to have materially improved old constructions designed to 105 carry these principles into effect, particularly along the lines of the insurance of practically perfect synchronization and accurate positioning of each blank at each operating station. To this end, I have shown 110 the side walls c⁴ and c⁵ of the bed C, throughout portions of their lengths from their rear ends, provided with flanges c⁶ and c⁷, respectively, forming oppositely-disposed 115 tracks for the channeled blocks 21 and 22, 120 respectively, forming oppositely-disposed tracks for the channeled blocks 21 and 22, 125 respectively, forming oppositely-disposed tracks for the channeled blocks 21 and 22, 130

which are reciprocably slidable thereon. The upper face of each of these blocks 21 and 22 is transversely channelled—or formed with ribs which provide a transverse channel—for the reception of an end of the cross-bar 23 in which said end is bolted (see Fig. 1), said cross-bar thus bridging said blocks and reciprocating therewith. Over this cross-bar 23 are provided the guide-bars 24 and 25, serving a double function, as will hereinafter appear, said bars being each provided with bosses at the ends thereof through which said bars are bolted to the bed-plates E and E', whereby a longitudinal slot is provided for reciprocation of the cross-bar 23, as clearly shown in Fig. 1. Each of these guide-bars 24 and 25 includes a vertically extending wing 26, the function of which will be hereinafter set forth. Through these rigidly connected blocks 21 and 22 the blank-advancing mechanism is driven, and for the reasons hereinbefore set forth it is essential that said blocks move in practically absolute synchronism.

To insure this essential synchronous reciprocation, I provide a solid casting which includes the shaft 27, the crank-arms 28 and 29 at the ends thereof, respectively, and the actuating crank-lever 30. The shaft 27 is suitably journaled in bearings in a supplemental frame 31 which I have shown bolted to the under side of the bed C. The ends of the arms 28 and 29 are provided with bosses 32 and 33, respectively, carrying the crank-pins 34 and 35 upon which the links or connecting-rods 36 and 37 are mounted, the outer ends of said links being similarly mounted upon wrist-pins 38 and 39 carried by bosses 40 and 41 with which the blocks 21 and 22 are provided, respectively. It will be apparent that the blocks 21 and 22 will be reciprocated upon rocking the shaft 27, and due to the rigidity of structure will reciprocate in practically perfect synchronism after initial accurate alignment.

The main power shaft 42 is journaled in bearings provided by in lugs or brackets 43 projecting from both legs of the inverted U-shaped frame B, and I have shown this shaft driven by means of a pulley 44 thereon adapted to be connected in the usual manner with any suitable source of power. Upon what I have considered—and shall proceed to consider—the left leg of said frame B is mounted the gear 45, positioned to mesh with a pinion 46 on the shaft 42. This gear 45 also constitutes a crank-wheel, being provided with the crank-pin 47 on which is mounted one end of the connecting-rod 48 the other end of which is adjustably connected, in a common and well-known manner, to the end of the crank-lever 30 on the shaft 27, a boss 49 provided at the end of said lever carrying the crank-

pin 50. It will thus be seen that upon rotation of the shaft 42 the lever 30 will be oscillated and the shaft 27 rocked, thereby reciprocating the blocks 21 and 22 in the manner set forth.

As hereinbefore explained, the blank-advancing mechanism comprises two separate and individual instrumentalities, located right and left, respectively, of the middle line of the machine. These instrumentalities are opposite counter-parts, wherefore a detailed description of one thereof will suffice for both. Referring more particularly to Figs. 10, 11, 12 and 13, wherein I have illustrated in detail the right-hand instrumentality, it will be seen that the same comprises a pair of spaced and rigidly connected feed-bars 51 and 52, the latter being adjustably bolted to a block 53 which straddles the cross-bar 23, and which is mounted to reciprocate longitudinally in a suitable way in the bed-plate E (see Fig. 12), the other ends of these feed-bars being slidably supported in a corresponding way in the other end of said bed-plate (see Fig. 13). It will be seen, therefore, that upon reciprocation of the blocks 21 and 22, and therewith the cross-bar 23, the feed-bars 51 and 52 will be longitudinally reciprocated.

Pivottally mounted between the bars 51 and 52 at the extreme rear ends thereof is the rearwardly projecting blank-engaging hook or pawl 54. This hook or pawl is yieldingly held in engaging position by means of a spring-pressed plunger 55 in the spacing block 56 acting against said pawl in the manner of a bell-crank lever (see Fig. 11), a stop 57 limiting movement of said pawl under action of the spring. In engaging position, the hook or pawl 54 is raised slightly above the plane of the upper faces of the bars 51 and 52, and a blank having been properly positioned for engagement thereby, upon the rearward stroke of reciprocation of said bars said hook or pawl will be depressed against the action of the spring and pass under the positioned blank. When said hook or pawl clears the rear edge of the blank, it is again spring-pressed to engaging position, and upon the forward stroke of reciprocation of said bars engages said blank and advances the same into the machine a distance approximately equal to the length of the stroke of reciprocation. The blanks may be successively positioned for engagement in any desired manner, as by hand, or, as illustratively suggested (Figs. 1 and 3), by feed-rollers 58 58 in a common and well-known manner.

Positioned to engage the rear edge of the blank thus advanced by the hook or pawl 54, at the end of the next rearward stroke of reciprocation of the feed-bars, is the pawl 59, pivotally mounted between said bars and spring-pressed to engaging position. This

pawl 59 is similarly depressed by the advanced blank during the rearward stroke of reciprocation of the feed-bars—said blank being held against rearward movement in a manner to be hereinafter described—and having cleared said blank is again raised to engaging position, engaging the rear edge of said blank upon the next forward stroke of reciprocation and advancing the same another step and to position for delivery, on the next forward stroke, to the notching mechanism. Upon this next succeeding forward stroke, the blank is similarly engaged by a similar spring-pressed pawl and advanced into said notching mechanism. During the next succeeding rearward stroke of reciprocation of the feed-bars, the notching operation is performed, the blank being at rest, and the similarly depressible spring-pressed pawl 60 (Fig. 6) carried back under said blank and to engaging position at the rear edge thereof, the pawl 59 now being in engaging position with respect to the next succeeding blank for advancement of the same to the notching mechanism. The next forward stroke of reciprocation advances the notched blank another step and into position intermediate the notching and the edging mechanism, and another blank into the notching mechanism. During the next rearward stroke of reciprocation, the notching and edging mechanisms are again operated while the blanks are at rest in said mechanisms, respectively, and another similarly depressible spring-pressed pawl 61, properly positioned, is carried back under the blank in said intermediate position and to engaging position at the rear edge thereof, the pawl 59 now being in engaging position with respect to another blank to be operated upon and the pawl 60 in engaging position with respect to the blank which has just been notched. The next forward stroke of reciprocation advances all blanks in the manner described, carrying an edged blank to position intermediate the edging and the forming mechanisms, and thence by the pawl 62 into the forming mechanism.

To prevent rearward movement of the advanced blanks with rearward movement of the feed-bars 51 and 52, after positioning of said blanks, I provide a recessed bar 63, secured at its rear end to the bed-plate E through the interposition of an angle-bar 64 (Fig. 12), paralleling the feed-bars 51 and 52, and secured at its forward end directly to said bed-plate where it forms one side of the aforesaid guideway for the feed-bars. Within the longitudinal recess in the bar 63, I mount a series of stop-pawls 65. These pawls are similarly depressible and spring-pressed to engaging positions, whereby they are non-interferent with forward movement of the blanks but are adapted to engage the rear edges of the latter suc-

sively when positioned by the pawls 59, 60, 61, etc., and prevent rearward movement thereof with the feed-bars 51 and 52. I have shown in Fig. 12 a manner of pivoting these stop-pawls, but have not otherwise illustrated the same in detail, as it may be assumed that in all respects they correspond in construction, mounting and spring-pressure operation to the pawls 59, 60, 61, etc.—examples of a common and well-known expedient.

One of the series of stop-pawls 65— and it is to be remembered that I am now describing one of two oppositely located and counterpart instrumentalities which combine to make up the advancing mechanism—checks rearward movement of a blank in position for further advancement into the notching mechanism. The next stop-pawl in advance thereof checks rearward movement of the advanced blank when properly positioned in the notching mechanism. The next stop-pawl checks rearward movement of the further advanced blank, and the next said blank when the same is properly positioned in the edging mechanism. The next stop-pawls perform the same function in connection with the delivery of the blank to the forming mechanism.

As I have stated, the machine of the present invention is primarily designed to be operated at comparatively great speed. This naturally involves rapid reciprocation of the feed-bars which results, even when suitable frictional braking means are employed, in more or less of an "overthrow" of each blank in attempting to bring the same to position at each of the operating stations, due to inertia. In fact, as suggested, it may be said to be necessary to slightly overthrow each blank in order to insure against insufficient advancement, bearing in mind the requisite of practically perfect and invariably uniform ultimate positioning. Therefore, it would seem to be essential that means be provided to quickly and dependably return each over-thrown blank to engagement with the stop-pawls at each operating station. Furthermore, it is also to be remembered that such means should be of a character to permit ready access to the entire path of travel of the blanks at any time, when desired, for any reason but particularly for the purpose of facilitating the removal of blanks which have been distorted or have become "jammed" on account of inherent imperfections or other causes.

With these ideas in mind, I provide a transverse horizontal shaft 66 having bearings in brackets 67 bolted to the legs of the inverted U-shaped frame B. Upon this shaft are pivotally mounted the vertically swinging bars 68 and 69, positioned substantially above and normally parallel to the bars 63. Integral with or suitably

mounted upon each of the guide-bars 24 and 25, is the boss or post 70, pivoted for horizontal oscillation on which is the latch-arm 71 adapted to be manually controlled by the lever 72 which constitutes an extension thereof. As shown in Fig. 2, the end of said latch-arm 71 is notched for the reception of a catch-plate 73, suitably secured to the end of each of the bars 68 and 69, which 10 catch-plate is also provided with an inter-engaging notch. A spring 74 in tension between said latch-arm 71 and a suitable anchorage on the web or wing 26 tends to yieldingly retain said latch-arm in engaging position, whereby, when the ends of said bars 68 and 69 are in latching engagement therewith they are releasably held in the normal positions indicated. It will be seen 15 that through the instrumentality of the levers or handles 72, the ends of said bars 68 and 69 may at any time be released and the latter swung to positions as indicated by the dotted lines in Figs. 1 or 8.

The bars 68 and 69, together with their 20 appurtenances, as hereinafter described, are opposite counterparts, wherefore a description of one will suffice for both thereof. Pivoted to each of said bars are the two oscillating fingers 75 and 76, the length of 25 each of which is such that when in vertical position it snugly contacts with a blank underneath the same. Mounted in the recess of each of the bars 63, in a manner best shown in Figs. 10, 11 and 13, are two idler rollers 77 and 78, the same being located immediately below the fingers 75 and 76, respectively. As will be apparent from Fig. 13, the periphery of each of these rollers projects slightly above the path of 30 travel of the blanks, whereby the same operate to eliminate excessive forces of friction upon the oscillation of said fingers in a rearward direction, the ends of said fingers frictionally engaging the blank and co-operating with said rollers to return the blanks 35 to engagement with the stop-pawl, as hereinbefore set forth.

These fingers 75 and 76 are actuated through the medium of a rod 79 to which 40 the end of each of said fingers is pivoted, said rod being pivoted at the end of a crank-arm 80 keyed to the shaft 66. When these fingers are in the positions illustrated in Fig. 3, the ends thereof are raised clear 45 of the advancing blanks. It will be apparent that said shaft 66 may be rocked to operate through said rod 79 to swing said fingers rearwardly, whereby the latter will co-operate with said rollers 77 and 78, respectively, to return over-thrown blanks 50 therebetween to engagement with the stop-pawl which control proper positioning. While each blank is twice brought to a condition of rest prior to delivery to the notching mechanism, and once to a position of 55

rest between said notching mechanism and the edging mechanism, it is obvious that there is no necessity for the employment of retracting or returning fingers elsewhere than at the notching and edging stations, 70 these being the only places where accurate positioning must be insured. The fingers 75 and 76 are normally yieldingly retained in retracted and inoperative positions by means of a coil spring 81, in tension between 75 the finger 75 and a suitable anchorage on the bar 68 (or 69).

It will be apparent that when the bars 68 and 69 are unlatched and swung to position as substantially as illustrated in either 80 Fig. 1 or Fig. 8, they will carry therewith the rods 79 and the fingers 75 and 76, whereby the entire path of travel of the advancing blanks, from the feeding station to the forming mechanism, is exposed and the advancing blanks accessible for the purposes hereinbefore set forth.

In Fig. 16 I have shown the flat blank *k* which is to be formed into a lock-seamed can body, and in Fig. 17 I have shown the 90 same after the first operation thereon. This first operation is known as the notching operation. Of course, the end edges of the blank might be bent over to form oppositely disposed hooks extending throughout 95 their entire lengths, but this would be objectionable on account of the fact that under such circumstances, when the ends of the body were flanged for the purpose of double seaming the heads or ends thereto, each of 100 the flanges would include four layers of metal at the point where the end edges were interhooked. This would result in a protuberance which would interfere with the formation of an hermetic double-seam in 105 what is known as the heading operation. Therefore, it has been the practice to notch the blank in such manner that when the end edges thereof are bent to inter-engaging hook-form, those portions at the ends of 110 said edges which form parts of the flanges, are merely overlapped, whereby no part of the flange comprises more than two layers of metal, which is unobjectionable.

The notching mechanism and the advancing means must necessarily be correlative to the extent of insuring accurate positioning of the blank by the latter in the former, and performance of the notching operation and withdrawal of the notching dies while the 115 blank to be operated upon is at rest. Furthermore, it is to be remembered that the entire machine is designed to be operated at high speed, and it will be apparent that the notching dies must operate and be withdrawn from the path of travel of the blanks during the rearward stroke of reciprocation of the feed bars 51 and 52.

There are doubtless many ways in which a blank may be notched to effect the results 120

to which I have referred. One of these ways I have illustrated in Fig. 17, which shows the corners cut away at one end edge of the blank and substantially V-shaped notches cut or punched near the ends of the opposite edge thereof. By reference to Fig. 18, it will be seen that when the blank notched in this manner is "edged," the ends of each edge will be merely overlapped in the forming operation.

Like the advancing means, the notching mechanism comprises two separate instrumentalities, mounted right and left of the middle line of the machine, respectively. With the exception of the configuration of the notching dies, these instrumentalities are opposite counterparts and a detailed description of one thereof will suffice for both. Each comprises a frame which includes a horizontal base plate 81 secured to one of the bed-plates E and E' having upwardly projecting wings or legs 82 and 83 bridged by a web 84.

Suitably journaled in bearings in the side walls of the bed C is the shaft 85, keyed on which are the mutilated pinions 86 and 87 the teeth of which mesh with the teeth of racks 88 at the lower ends of the vertical shafts 89 and 90, respectively, which are reciprocable in slide-bearings through the bed-plates E and E' and the base-plates 81 thereon. It will be seen that the shafts 89 and 90 will be reciprocated vertically when the shaft 85 is rocked.

At the upper end of each of the shafts 89 and 90 I prefer to provide a cylindrical head 91 adapted to fit within a socket 92 in the base of a tool or die holder which comprises a preferably wedge-shaped guide portion 93 integral with a shorter elongated portion 94. At or near the ends of the elongated part 94 are the tool-holding blocks 95 and 96, each of these blocks being provided with a vertical recess for the reception of the cylindrical body portion of a die 97, the recess terminating short of the upper end of the block and being so dimensioned relative to the die that the latter projects slightly laterally from the former thereby said die may be clamped within said recess by means of a plate 98. These tool-holding blocks are longitudinally adjustable with reference to the part 94, for which purpose I have shown the latter provided with tongues 99 and 100 fitting into corresponding grooves in said blocks 95 and 96, said part 94 being also provided with a longitudinal slot or bore 101, of rectangular cross-sectional configuration, to which a longitudinal groove or channel 102 is open. Slidably within the slot or bore 101 is the square head of a bolt 103 which passes through the tool-holding block and the clamping plate, with a clamping nut 104 at the outer end thereof. It will be seen that in this manner not only may said tool-hold-

ing block be rigidly secured in any desired relative position longitudinally on the part 94, but at the same time contributes to the clamping of the die in its holding block, this clamping being augmented by the provision of a cap-screw 105 passing through the clamping plate 98 and into the block. The die is rendered vertically adjustable, within limits, by means of a set-screw 106 at the top of the block.

In order to render the tool carrier removable in its entirety, I provide the head 91 on each of the shafts 89 and 90 with a circular bore therethrough adapted to register with a corresponding bore 107 in the base of said carrier, as clearly shown in Fig. 6^a, through which a pin 108 may be passed, this pin being preferably provided with a circular groove 109 into which a set-screw 110 is adapted to project to retain said pin in place.

The dies 97 on one side of the machine are adapted to punch out the circular notches 111 at one end-edge of the blank (Fig. 17), and the dies on the other side of the machine are adapted to punch out the substantially V-shaped notches 112 in the other end-edge of the blank, these end-edges being supported on plates 113, which provide female dies, these plates being suitably mounted on the base plate 81 of the tool-carrier. Of course, this base plate and the bed plate to which the same is secured are suitably mounted for the passage therethrough of the scrap.

Suitably journaled in bearings in the side walls of the bed C is a horizontal shaft 114, driven from the main power shaft 42 by means of the pinion 46 on the latter the teeth of which mesh with the teeth of an interposed idler pinion 115 mounted on a bracket 116 secured to and depending from the bed C, which, in turn, meshes with the gear 117 on said shaft 114. On this shaft 114 is mounted an eccentric 118 carrying the eccentric-strap 119 at the end of the connecting-rod 120 pivoted to the end of the short lever 121 which is keyed to the shaft 85. It will therefore be seen that upon rotation of the shaft 42, the shaft 85 will be rocked to operate the notching dies in the manner described, and the parts are obviously so adjusted that the tool-holders are reciprocated when a blank has been brought to a condition of rest in the notching mechanism, being elevated to clear said blank prior to the return stroke of reciprocation.

From the notching mechanism the advancing pawls first advance the notched blank to an intermediate position and thence to the edging mechanism. This edging mechanism is in all material respects substantially identical to that shown and described in patent to Paul R. Hahnemann, No. 1,200,190, dated October 3, 1916. It consists of two some-

what similar devices, one on the right-hand side of the machine for turning up one end-edge of the blank to form a hook and the other on the left-hand side of the machine 6 for turning down the other end-edge and forming an oppositely disposed hook, whereby said hooks may be brought into inter-engagement when the blank is bent to cylindrical shape in the forming mechanism. The 10 edging device on the right hand side of the machine comprises an edge-supporting bar 122, preferably of tool steel, carried by and therefore adjustable with the bed-plate E, the upper face of which is slightly beveled. 15 With this bar 122 is adapted to co-operate the bar 123 at the end of what may be termed the arm 124 of a heavy casting in the general form of a bell-crank lever pivoted on the stud 125 carried by a bracket integral with 20 the bed-plate E. The blank k is positioned to be clamped near the edge thereof between said bars 122 and 123, the operative force of the latter being inclined from the horizontal to conform to the beveled face of the 25 bar 122, whereby the projecting edge of said blank is slightly bent downwardly. I prefer that the length of these clamping bars 122 and 123 should be slightly in excess of the width of the blanks to be hooked, or 30 the length of the can body to be formed.

At the end of the other arm 127 of what I have called a bell-crank is mounted a roller 128 (dotted lines in Fig. 7) spring-pressed against the cam 129 on the horizontal shaft 35 114. The configuration of the cam 129 is such that upon rotation of the shaft 114 the arm 127 of said bell-crank lever will be oscillated to intermittently raise and lower the clamping bar 123 at the end of the arm 40 124 of said lever, operation being so timed that said arm 124 is depressed immediately following the positioning of a notched blank in the edging mechanism. As stated, it will be seen from the beveled configuration of 45 these bars 122 and 123 that not only do they operate to clamp the blank k near the right-hand edge thereof, but also slightly bend this edge downwardly. A hub 130, which is an integral part of the bed-plate E, is provided with an upwardly projecting lug 131 which not only provides a stop adapted to engage a detent 132 and limit upward movement of the arm 124, but also serves as an abutment 50 against which acts the spring 216 which normally holds said arm 124 in its raised position and the roller 128 against the face of the cam 127.

Suitably pivoted to the bed-plate E is the elongated swinging-lever 134, at the end 60 of the lower arm of which is mounted a roller 135 in the cam-groove 136, and at the end of the upper arm of which is mounted the edging bar or plate 137. In substantially the same manner as that shown and 65 described in detail in the Hahnemann pat-

ent, aforesaid, lateral movement of the roller 135 in the cam-groove 136 throws the edging bar or plate 137 in the direction of the clamping bars 122 and 123, at the same time directing the former upwardly, whereby the 70 extreme edge of the blank which projects from said clamping bars is engaged and bent upwardly to hook-form, as shown in Figs. 18 and 19.

The edging tool or bar 137, is of such 75 length and so positioned that the edge of the blank k is engaged between the notches only, as indicated in Fig. 18. Obviously, the configuration of the cam-groove 136 is such that the edging tool or bar 137 is operated immediately following operation of the clamping bars 122 and 123.

The edging mechanism on the left-hand side of the machine is substantially similar to that just described, although the hook at 85 this edge of the blank must be oppositely disposed relative to the hook formed by the mechanism on the right-hand side of the machine—that is to say, in the present case, downwardly. Therefore, the upper face of 90 the supporting or clamping bar 122, correspondingly mounted on the bed-plate E', is not beveled, and this edge of the blank remains flat when engaged by the clamping bar 123' on the arm 124' of a correspond- 95 ingly shaped and operated bell-crank lever. The lever 134', which carries the edging tool or bar 137', is operated in precisely the same manner as the corresponding lever on the other side of the machine, but in this case is 100 of such configuration and so pivoted that when the tool or bar 137' is swung inwardly, it engages the upper face of the blank and bends the same downwardly to hook-form, as indicated in Fig. 7 and as substantially 105 shown and described in detail in the Hahne- man patent, aforesaid. Obviously, the edging operations are performed simulta- 110 neously, and immediately thereafter the clamping bars are raised to free the blank 115 for advancement to the forming mechanism upon the next forward stroke of reciproca- 120 tion of the feed bars 51 and 52, each blank being brought into an intermediate position prior to being delivered to and properly po- 125 sitioned in said forming mechanism.

The forming mechanism proper—that is to say, the means for bending or curling the blank into substantially cylindrical form, inter-hooking the hooked end-edges thereof and compressing these inter-hooked edges into a substantially solid seam—is located within the inverted U-shaped frame B, and comprises, first, an expanding horn or man- 125 drel 138 which, to all intents and purposes, is substantially similar in general construction and operation to that shown and de- 130 scribed in the Hahnemann patent, aforesaid. Obviously, this mandrel, when expanded, is as nearly as practicable in cylindrical form 130

and of the same diameter as the internal diameter of the desired size of the can-body to be formed.

Like the mandrel of the Hahnemann patent, the mandrel 138 comprises three sections, a middle section 139 at the end and preferably forming an integral part of an arm 140 bolted to the end of the bed C, and two substantially similar and oppositely disposed outside sections 141 and 142, the outer faces of which are of the desired cylindrical contour and the upper and lower faces of said middle section 139 generally conforming to such contour, whereby the whole has the general form of a cylinder. The middle section 139 is provided with the oppositely located slots or recesses 143 and 144 wherein are pivoted lugs 145 and 146 projecting from the interior faces of said outside sections 141 and 142, respectively, whereby the latter may be swung outwardly to have the effect of expanding the mandrel.

At the upper end of the inverted U-shaped frame B are provided vertical ways or tracks for the longitudinally reciprocating, vertically-disposed bars 147 and 148, one on each side of said frame, the lower ends of said bars being recessed for the reception of a cross-bar 149 which is suitably secured in the recesses. This cross-bar 149 is located immediately above the horn or mandrel 138, parallels the axis thereof and is provided with a longitudinal channel in its lower face within which is mounted the pressing or retaining bar 150. This bar 150 is mounted for limited vertical reciprocation in said channel, compression coil-springs (Figs. 14 and 15) being provided to yieldingly retain said bar in what may be termed a downwardly protruding position and in contact with said horn or mandrel 138. The rear end 151 of said bar 150 is upwardly bent, as shown in Fig. 15, whereby a blank in process of advancement to the forming mechanism may be readily passed under said bar and to proper position over said mandrel, in which position it is now yieldingly held by said bar 151, as best shown in Fig. 14.

The now positioned blank is to be curled around said mandrel to substantially cylindrical shape, and for this purpose I provide two wings 152 and 153, each pivoted in the cross-bar 149 and adapted to be vertically oscillated toward and from the mandrel. A portion of the inner face of each of said wings is of substantially cylindrical contour the diameter of which approximates that of the mandrel when expanded, the major portion of which, when said wings are depressed to their lowermost positions they are adapted to envelop. To the outer faces of the wings 152 and 153 are pivoted the connecting-rods 154 and 155, respectively. These connecting-rods 154 and 155 are pivoted at their upper ends to the ends of lev-

ers 156 and 157, respectively, which are mounted for independent oscillation on a common pivot-pin 158 in the frame B.

Journaled in bearings in brackets 159 and 160 mounted on the base A is the longitudinally-disposed combined double-crank and cam-shaft 161. This shaft is driven from the main power shaft 42 by means of the spiral gears 162 and 163 on said shafts, respectively. The double-crank 161 in said shaft is provided with what may be termed a double crank-pin, the same comprising the portion 164 to which the lower end of a rod 165 is pivoted and the portion 166 upon which the lower portion of a rod 167 is pivoted, these portions 164 and 166 of said crank pin being slightly off-set from each other for a purpose which will be hereinafter set forth. The upper end of the rod 165—considered, for the time being, as a whole—is pivoted to the rear end of the lever 156, and the upper end of the rod 167—similarly considered—is pivoted to the rear end of the lever 157. It will be apparent that upon rotation of the shaft 161 the levers 156 and 157 will be oscillated, effecting through the connecting-rods 154 and 155 vertical oscillation of the wings 152 and 153. The parts described are so dimensioned, proportioned and adjusted that when the rods 165 and 167 are in their most depressed positions, the wings 152 and 153 will be in raised positions, as indicated in Figs. 14 and 15, and when said rods are in their most elevated positions, said wings will be depressed to envelop the mandrel 138, as shown in Figs. 3 and 4. The gears 162 and 163 are so proportioned that the enveloping operation is performed immediately following the positioning of a blank in the forming mechanism and withdrawal of said wings prior to the next forward stroke of reciprocation of the feed-bars 51 and 52.

In order that this blank-forming operation will also effect automatically the inter-hooking of the edged ends of the blank, it is essential, first, that the mandrel be in what may be termed the contracted condition; second, that the end-edge of the blank which is provided with an outwardly-directed hook be first brought to position and the end edge of the blank which is provided with an inwardly directed hook be then brought to overlapping relationship with said first-mentioned end-edge; third, that the forming wing first to operate is also first to be withdrawn, whereby the resiliency of the metal of the blank will cause the out-hooked end-edge of the same to spring into engagement with said in-hooked end-edge when the other forming wing is withdrawn immediately following withdrawal of its opposite counterpart; and, fourth, that the mandrel be expanded

substantially simultaneously with withdrawal of the wing last to operate, whereby the inter-hooking operation is completed and the inter-hooked relationship maintained for the compressing operation. It is for the purpose of insuring operation and withdrawal of the wing 152 slightly in advance of operation and withdrawal of the wing 153 that I slightly offset the crank-pin portions 164 and 166 from each other. In this manner, I provide for the above-mentioned second and third essentials of this forming mechanism.

Journalized in bearings in the forward end of the bed C is the comparatively short horizontal shaft 168. At the outer end of this shaft is mounted an arm 169 having at the free end thereof a roller 170 adapted to travel in the cam-groove 171 in the cam-disc 172 secured to the inner face of the gear 117 on the shaft 114. The cam-groove 172 is of such contour that the shaft 168 is rocked immediately following withdrawal of the forming wing 152 and substantially simultaneously with withdrawal of the forming wing 153. The pivoted outside sections 141 and 142 of the mandrel 138 are provided with rearwardly projecting lugs or bosses 173 and 174, respectively, and said shaft 168 is provided with forwardly projecting arms 175 and 176 the free ends of which are located immediately below the lugs or bosses 173 and 174, respectively. For purposes of adjustment, I provide at the ends of said arms 175 and 176 the screws 177 and 178, respectively, the heads of which are adapted to impinge against the lower faces of said lugs or bosses 173 and 174, whereby, when said shaft 168 is rocked, said arms 175 and 176 will be raised and operate against the lugs or bosses 173 and 174 to swing said outside mandrel-sections 141 and 142 outwardly for a limited distance to have the effect of expanding said mandrel, as and for the purposes hereinbefore set forth. The blank is now in the condition illustrated in Fig. 21 and ready for the seam-compressing operation.

During the hereinbefore described blank-forming operation, the mandrel 138 is supported only through the arm 140, and while this is sufficient to support said mandrel against the yielding forces of the forming operation, it is insufficient, in the absence of any re-inforcing support or supports, to provide adequate rigidity to withstand the positive forces of the seam-compressing operation, the latter being applied more or less in the manner of a blow and the forces being comparatively necessarily intensive in order to insure a permanent and air-tight seam. The end edges of the blank being inter-hooked on the lower right side of the mandrel, the compressing forces must be necessarily upwardly directed, and it has

been found to be essential, therefore, to provide some means for re-inforcing the normal mandrel-support in order to provide sufficient rigidity, not only to insure the formation of a substantially perfect seam, but to prevent displacement of the mandrel under the repeated blows of the compressing tool or die.

To effect this essential rigidity and stability of structure I mount the pressing or retaining bar 150 in the channeled cross-bar 149 in such manner that upon depression of the vertical bars 147 and 148 the normal gap between the upper face of the bar 150 and the base of the channel in the cross-bar 149 is closed, thus forming, with the bar-depressing means which I am now about to describe, a substantially solid structure to support the mandrel against the forces of the compressing operation.

This bar-depressing means comprises the levers 179 and 180 pivoted at 181 to form a toggle joint and their opposite counterparts on the other side of the frame B. The levers 179 and 179' are pivoted to the vertically reciprocating bars 147 and 148, respectively, and the levers 180 and 180' are fixed at the ends of, or the latter, as shown may be integral with a shaft 182 keyed in an eccentric sleeve 183 journalized in bearings at the upper end of the inverted U-shaped frame B. The toggles are operated from the shaft 158 by means of an arm or lever 184 fixed on said shaft, to the end of which is pivoted the end of the link or connecting rod 185, the other end of which is pivoted on the toggle-pivot 181, whereby, when said shaft 158 is rocked, the toggles will be operated to depress the bars 147 and 148 and therewith the cross-bar 149 and hold the same rigidly in depressed position against the forces of the seam-compressing operation. The shaft 158 is rocked to operate said toggles by means of a lever 186 —forming with the arm 184 a bell-crank—which is oscillated by the connecting-rod 187 pivoted to the free end thereof and being provided at its other end with a roller 188 impinging against a cam 189 on the shaft 161, these parts being so proportioned and adjusted that the toggles are operated immediately following withdrawal of the wings 152 and 153 after the forming operation.

The seam-compressing tool or die 190 is mounted in a block 191 slidable in suitable vertical ways provided in brackets 192, 192 secured to the frame B. This block 191 is provided with a suitable recess within which is pivoted the end of a connecting-rod 193, the other end of which is mounted on the crank-pin 194 of the double-crank 195 in the shaft 196, this being the shaft on which the gear 45, to which I have hereinbefore referred, is fixed. It will be ap-

85

105

110

115

120

125

130

parent that upon rotation of said shaft 196, the connecting-rod 193 will be operated to reciprocate the block 191 and therewith the compressing-tool or die 190 in the manner and for the purpose hereinbefore set forth. Obviously, these parts are so proportioned and adjusted that this compressing operation takes place immediately following engagement of the inter-hooked end edges of 10 the blank and operation of the toggles.

Operation of the toggles is yieldingly resisted by means of a coil-spring 197 in tension between the end of the lever 186 on the shaft 158 and a pin or bracket 198 mounted 15 on the frame B. It will be apparent that said spring 197 tends to return said toggles to and retain the same in inoperative positions and the cross-bar 149 in raised position.

20 It will furthermore be apparent that the wings 152 and 153 should be actuated by yielding forces, and for this purpose I provide a link-and-pin connection 199 between each of the rods 165 and 167 and the ends of 25 the levers 156 and 157, respectively, with a compression spring 200 interposed therein, all of common and well-known construction, assembly and operation.

I have shown the middle section 139 of the 30 mandrel provided on its lower face with a longitudinal groove or channel 201 into which the inter-hooked parts of the blank are pressed by the die 190 during compressing operation, as clearly shown in Fig. 22, 35 not only to form a seam, but also to cause the protuberance to be formed on the inside, instead of on the outside, of the can body.

The blanks, during process of advancement through the machine, are supported 40 upon a bar 202 the rear end of which is bolted, riveted or otherwise suitably secured to the cross-bar 23 and which therefore reciprocates therewith. To the forward end of the bar 202 is secured an extension-arm 203, 45 this arm extending through and substantially forming a part of the mandrel 138, sliding in suitable groove or channel in the upper face of the middle section 139 of said mandrel. This arm is provided with spring- 50 pressed pawls, similar to those described in connection with the feed bars 51 and 52, the first 205 being adapted to engage the can-body after the blank-forming and seam-compressing operations—which, as has been 55 explained, take place during the rearward stroke of reciprocation of the cross-bar 23 and therefore the bar 202—and force said body off the mandrel 138 and onto the horn 204 which projects therefrom. The next 60 pawl 206 on said arm is adapted to advance said formed can-body another step along said horn. This horn 204 is adapted to direct the can-bodies into and through a side-seam soldering machine, such as, for example, 65 that shown and described by me in a prior

patent granted to me August 10, 1920, No. 1,349,044. As a matter of fact, the soldering machine of my said co-pending application may be said to be a continuation—if not actually a part—of the machine of this application, the former being preferably driven by means of sprockets 207 and 208 on the main power shaft 42 of the present machine (Fig. 4), as suggestively illustrated in Fig. 1 and Fig. 3, wherein the main driving shaft 209 of the soldering machine is shown having chain-and-sprocket connection with said shaft 42.

I have explained that the shaft 182 is keyed in an eccentric sleeve 183 which is 80 journaled in bearings at the upper end of the frame B. Fixed upon this sleeve 183 is a collar 210 which is provided with a hand-operated lever 211 projecting to readily accessible position, whereby said sleeve 183 85 may be rocked. This sleeve being eccentric, as indicated in Figs. 4 and 7, it will be apparent that by swinging the lever 211 the shaft 182 will be raised, operating through the toggle levers to raise the cross-bar 149. 90 This is for the purpose of effecting clearance for the removal of blanks which, for any reason, have become "jammed," on account of inherent imperfection, distortion or otherwise, in the forming mechanism. 95

It is believed that it will be apparent from the foregoing description that in the machine of the present invention the advancing mechanism and the operating mechanisms are so constructed, assembled, operated and inter-related that the machine can be successfully operated at comparatively high speed—at a speed high enough, for instance, to effect deliveries of formed can-bodies to the flanging machine, and subsequently to the heading machine as rapidly as the flanging and heading operations can be performed by such machines; furthermore, that the machine of the present invention may be easily and readily adapted to the 100 handling of blanks for the formation of can-bodies of various shapes and sizes; furthermore, that all parts thereof are as readily accessible, for purposes of repair or replacement, as is reasonably possible in a complicated machine of this character; furthermore, that practically the entire path of travel of the blanks, in process of formation, may be rendered accessible at any time, for 110 the purposes of removal of distorted and 115 "jammed" blanks and requisite readjustment.

Furthermore, I have hereinbefore referred to the necessity for quick stoppage of the forming machine, in case of emergency 125 without stopping the appurtenant soldering machine, wherein premature cooling of an incompletely soldered can-body would be manifestly objectionable. With this idea in mind, instead of mounting the sprockets 130

207 and 208 directly upon the shaft 42, I mount upon the latter a sleeve 212, upon which said sprockets, as well as the driving pulley 44, are mounted, providing an ordinary clutch 213, operated in a common and well-known manner by a lever 214 at the rear end of a rod or shaft 215, for connecting and releasing to and from each other the sleeve 212 and the shaft 42, whereby the latter may be released and stopped; and thus stop operation of all of the mechanisms of the machine of the present invention, without stopping operation of the soldering machine driven from said sprockets 207 and 208.

15 Furthermore, it will be apparent that in a machine embodying the present invention, the notching, edging, bending and compressing tools, after operation thereof, are quickly withdrawn from the path of travel of the blanks, so that the periods of rest at each of the operating stations are of the shortest possible duration; furthermore, that each blank may be carried slightly beyond its proper position at each operating station

20 and, upon being released from its advancing means, is immediately returned to precise operative position; furthermore, that synchronism of movements of the oppositely-located and substantially counterpart instrumentalities for performing each of the notching, edging and bending operations is insured, and this with the advancing mechanism interposed between opposite parts thereof and without sacrifice of strength and

25 rigidity and with ready accessibility of both tools and work and facility of dimensional adjustment; furthermore, it will be apparent that where it is desirable that the applied forces be of a yielding character, they are of

30 such character, and that where initially yielding force-applying means should subsequently become or be made inflexible, this condition of substantial inflexibility is produced.

35 Many modifications of minor details of my improved can-body forming machine will doubtless readily suggest themselves to those skilled in the art to which it appertains, and I therefore do not desire to limit my invention to the specific construction herein shown and described.

40 I claim:

1. In a machine of the character described, the combination, with a series of mechanisms for successively forming can-bodies from flat sheet-metal blanks, said series comprising preliminary notching and edging mechanisms and final forming and seam-compressing mechanisms, of means for advancing said
- 45 blanks through the machine, bringing each thereof to a condition of rest at each operating station, in turn, means for checking rearward movement of each blank when in proper position at each of said stations, and connected means at each of the preliminary

notching and edging stations and having common actuating means for returning into engagement with said checking means such blanks as have been carried slightly beyond the same.

70

2. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, and yielding means at each of the preliminary notching and edging stations for returning into engagement with said checking means such blanks as are carried slightly beyond the same.

80

3. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, and horizontally reciprocating means at each of the preliminary notching and edging stations for returning into engagement with said checking means such blanks as are carried slightly beyond the same.

90

4. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, and connected means at a plurality of operating stations and having common actuating means for returning into engagement with said checking means such blanks as are carried slightly beyond the same.

100

5. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, and connected means at each of the preliminary

- at each operating station, in turn, means for checking rearward movement of each blank when in proper position at each of said stations, and yielding means at a plurality of operating stations and having common actuating means for returning into engagement with said checking means such blanks as are carried slightly beyond the same.
10. 6. In a machine of the character described, the combination, with a series of mechanisms for successively forming can-bodies from flat sheet-metal blanks, said series comprising preliminary notching and 15 edging mechanisms and final forming and seam-compressing mechanisms, of means for advancing said blanks through the machine, bringing each thereof to a condition of rest at each operating station, in turn, means 20 for checking rearward movement of each blank when in proper position at each of said stations, and horizontally reciprocating a plurality of operating means at stations and having common actuating means for 25 turning into engagement with said checking means such blanks as are carried slightly beyond the same.
7. In a machine of the character described, the combination, with a series of 30 mechanisms for successively forming can-bodies from flat sheet-metal blanks, said series comprising preliminary notching and edging mechanisms and final forming and seam-compressing mechanisms, of means for 35 advancing said blanks through the machine, bringing each thereof to a condition of rest at each operating station, in turn, means for 40 checking rearward movement of each blank when in proper position at each of said stations, and yielding means at each of the notching and edging stations and having common actuating means for returning into 45 engagement with said checking means such blanks as are carried slightly beyond the same.
8. In a machine of the character described, the combination, with a series of mechanisms for successively forming can-bodies from flat sheet-metal blanks, said 50 series comprising preliminary notching and edging mechanisms and final forming and seam-compressing mechanisms, of means for advancing said blanks through the machine, bringing each thereof to a condition of rest 55 at each operating station, in turn, means for checking rearward movement of each blank when in proper position at each of said stations, and inter-connected frictional means at each of the notching and edging stations 60 and having common actuating means for returning into engagement with said checking means such blanks as are carried slightly beyond the same.
9. In a machine of the character described, the combination, with a series of 65 mechanisms for successively forming can-bodies from flat sheet-metal blanks, said 70 series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, and means at more than one of said stations for returning into engagement with said checking means such blanks as are carried slightly beyond the same, said last-mentioned means being 75 mounted on a common supporting frame which is mounted for ready independent withdrawal to render accessible the path of advancement of said blanks.
10. In a machine of the character described, the combination, with a series of mechanisms for successively forming can-bodies from flat sheet-metal blanks, said series comprising preliminary notching and 80 edging mechanisms and final forming and seam-compressing mechanisms, of means for advancing said blanks through the machine, bringing each thereof to a condition of rest at each operating station, in turn, means for 85 checking rearward movement of each blank when in proper position at each of said stations, and yielding means at more than one of said stations for returning into engagement with said checking means such blanks as are carried slightly beyond the same, said last-mentioned means being 90 mounted on a supporting frame which is mounted for ready independent withdrawal to render accessible the path of advancement of said blanks.
11. In a machine of the character described, the combination, with a series of mechanisms for successively forming can-bodies from flat sheet-metal blanks, said series comprising preliminary notching and 95 edging mechanisms and final forming and seam-compressing mechanisms, of means for advancing said blanks through the machine, bringing each thereof to a condition of rest at each operating station, in turn, means for 100 checking rearward movement of each blank when in proper position at each of said stations, and frictional means at more than one of said stations for returning into engagement with said checking means such blanks as are carried slightly beyond the same, said last-mentioned means being mounted on a supporting frame which is mounted for ready independent withdrawal to render accessible the path of advancement of said blanks.
12. In a machine of the character described, the combination, with a series of mechanisms for successively forming can-bodies from flat sheet-metal blanks, said 105 series comprising preliminary notching and edging mechanisms and final forming and seam-compressing mechanisms, of means for advancing said blanks through the machine, bringing each thereof to a condition of rest at each operating station, in turn, means for 110 checking rearward movement of each blank when in proper position at each of said stations, and frictional means at more than one of said stations for returning into engagement with said checking means such blanks as are carried slightly beyond the same, said last-mentioned means being mounted on a common supporting frame which is mounted for ready independent withdrawal to render accessible the path of advancement of said 115 blanks.
13. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for 120 checking rearward movement of each blank when in proper position at each of said stations, and frictional means at more than one of said stations for returning into engagement with said checking means such blanks as are carried slightly beyond the same, said last-mentioned means being mounted on a common supporting frame which is mounted for ready independent withdrawal to render accessible the path of advancement of said 125 blanks.
14. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for 130 checking rearward movement of each blank when in proper position at each of said stations, and frictional means at more than one of said stations for returning into engagement with said checking means such blanks as are carried slightly beyond the same, said last-mentioned means being mounted on a common supporting frame which is mounted for ready independent withdrawal to render accessible the path of advancement of said blanks.

ries comprising preliminary notching and edging mechanisms and final forming and seam-compressing mechanisms, of means for advancing said blanks through the machine, 5 bringing each thereof to a condition of rest at each operating station, in turn, means for checking rearward movement of each blank when in proper position at each of said stations, and means at certain stations for re- 10 turning into engagement with said checking means such blanks as are carried slightly beyond the same, said last-mentioned means being mounted on a common supporting frame which is mounted for ready independent withdrawal to render accessible the path of advancement of said blanks.

13. In a machine of the character described, the combination, with a series of mechanisms for successively forming can- 20 bodies from flat sheet-metal blanks, said series comprising preliminary notching and edging mechanisms and final forming and seam-compressing mechanisms, of means for advancing said blanks through the machine, 25 bringing each thereof to a condition of rest at each operating station, in turn, means for checking rearward movement of each blank when in proper position at each of said stations, and yielding means at certain 30 stations for returning into engagement with said checking means each blank which has been carried slightly beyond the same, said last-mentioned means being mounted on a frame which is withdrawable to render ac- 35 cessible the path of advancement of said blanks.

14. In a machine of the character described, the combination, with a series of mechanisms for successively forming can- 40 bodies from flat sheet-metal blanks, said series comprising preliminary notching and edging mechanisms and final forming and seam-compressing mechanisms, of means for advancing said blanks through the machine, 45 bringing each thereof to a condition of rest at each operating station, in turn, means for checking rearward movement of each blank when in proper position at each of said stations, and frictional means at certain 50 stations for returning into engagement with said checking means such blanks as are carried slightly beyond the same, said last-mentioned means being mounted on a common supporting frame which is mounted for 55 ready independent withdrawal to render accessible the path of advancement of said blanks.

15. In a machine of the character described, the combination, with a series of mechanisms for successively forming can- 60 bodies from flat sheet-metal blanks, said series comprising preliminary notching and edging mechanisms and final forming and seam-compressing mechanisms, of means for 65 advancing said blanks through the machine,

bringing each thereof to a condition of rest at each operating station, in turn, means for checking rearward movement of each blank when in proper position at each of said stations, and means at the notching and edging 70 stations for returning into engagement with said checking means such blanks as are carried slightly beyond the same, said last-mentioned means being mounted on a common supporting frame which is mounted for 75 ready independent withdrawal to render accessible the path of advancement of said blanks.

16. In a machine of the character de- 80 scribed the combination, with a series of mechanisms for successively forming can- bodies from flat sheet-metal blanks, said series comprising preliminary notching and edging mechanisms and final forming and seam-compressing mechanisms, of means for 85 advancing said blanks through the machine, bringing each thereof to a condition of rest at each operating station, in turn, means for checking rearward movement of each blank when in proper position at each of said stations, and yielding means at the notching and edging stations for returning into en- 90 gagement with said checking means each blank which has been carried slightly be- 95 yond the same, said last-mentioned means being mounted on a frame which is with- drawable to render accessible the path of ad- vancement of said blanks.

17. In a machine of the character de- 100 scribed, the combination, with a series of mechanisms for successively forming can- bodies from flat sheet-metal blanks, said series comprising preliminary notching and edging mechanisms and final forming and seam-compressing mechanisms, of means for 105 advancing said blanks through the machine, bringing each thereof to a condition of rest at each operating station, in turn, means for checking rearward movement of each blank when in proper position at each of said stations, and frictional means at the notching and edging stations for returning into en- 110 gagement with said checking means such blanks as are carried slightly beyond the same, said last-mentioned means being 115 mounted on a common supporting frame which is mounted for ready independent withdrawal to render accessible the path of ad- vancement of said blanks.

18. In a machine of the character de- 120 scribed, the combination, with a series of mechanisms for successively forming can- bodies from flat sheet-metal blanks, said series comprising preliminary notching and edging mechanisms and final forming and 125 seam-compressing mechanisms, of means for advancing said blanks through the machine, bringing each thereof to a condition of rest at each operating station, in turn, means for checking rearward movement of each blank 130

- when in proper position at each of said stations, a pivoted frame above said advancing means adapted to be swung vertically, and means carried by said frame and normally located at certain of said stations for returning into engagement with said checking means each blank which has been carried slightly beyond the same.
19. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, a pivoted frame above said advancing means adapted to be swung vertically, and means carried by said frame and normally located at the notching and edging stations for yieldingly returning into engagement with said checking means each blank which has been carried slightly beyond the same.
20. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, a pivoted frame above said advancing means adapted to be swung vertically, and means carried by said frame and normally located at certain of said stations for yieldingly returning into engagement with said checking means each blank which has been carried slightly beyond the same.
21. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, a pivoted frame above said advancing means adapted to be swung vertically, and means carried by said frame and normally located at certain of said stations for frictionally returning into engagement with said checking means each blank which has been carried slightly beyond the same.
22. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, a pivoted frame above said advancing means adapted to be swung vertically, and means carried by said frame and normally located at the notching and edging stations for yieldingly returning into engagement with said checking means each blank which has been carried slightly beyond the same.
23. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, a pivoted frame above said advancing means adapted to be swung vertically, and means carried by said frame and normally located at the notching and edging stations for frictionally returning into engagement with said checking means each blank which has been carried slightly beyond the same.
24. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, a pivoted frame above said advancing means adapted to be swung vertically, and means carried by said frame and normally located at certain of said stations for returning into engagement with said checking means each blank which has been carried slightly beyond the same, and releasable means at the free end of said frame for latching the same with the blank-returning means thereon in operative positions.
25. In a machine of the character described, the combination, with a series of mechanisms for successively forming can-bodies from flat sheet-metal blanks, said

- series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, a pivoted frame above said advancing means adapted to be swung vertically, means carried by said frame and normally located at certain of said stations for yieldingly returning into engagement with said checking means each blank which has been carried slightly beyond the same, and releasable means at the free end of said frame for latching the same with the blank-returning means thereon in operative positions.
26. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, a pivoted frame above said advancing means adapted to be swung vertically, means carried by said frame and normally located at certain of said stations for frictionally returning into engagement with said checking means each blank which has been carried slightly beyond the same, and releasable means at the free end of said frame for latching the same with the blank-returning means therein in operative positions.
27. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, a pivoted frame above said advancing means adapted to be swung vertically, means carried by said frame and normally located at the notching and edging stations for returning into engagement with said checking means each blank which has been carried slightly beyond the same, and releasable means at the free end of said frame for latching the same with the blank-returning means thereon in operative positions.
28. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, a pivoted frame above said advancing means adapted to be swung vertically, means carried by said frame and normally located at the notching and edging stations for yieldingly returning into engagement with said checking means each blank which has been carried slightly beyond the same, and releasable means at the free end of said frame for latching the same with the blank-returning means thereon in operative positions.
29. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, a pivoted frame above said advancing means adapted to be swung vertically, means carried by said frame and normally located at the notching and edging stations for frictionally returning into engagement with said checking means each blank which has been carried slightly beyond the same, and releasable means at the free end of said frame for latching the same with the blank-returning means thereon in operative positions.
30. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, means for checking rearward movement of each blank when in proper position at each of said stations, means at the notching and edging stations for returning into engagement with said checking means each blank which has been carried slightly beyond the same, and means at the forming and seam-compressing station for overcoming inertia of the blank being advanced thereto, both

said last-mentioned means and said returning means being bodily withdrawable, the latter, independently of all other mechanisms, to render accessible the entire path of 5 travel of said blanks.

31. In a machine of the character described, the combination, with a series of mechanisms for successively forming can-bodies from flat sheet-metal blanks, said 10 series comprising preliminary notching and edging mechanisms and final forming and seam-compressing mechanisms, of means for advancing said blanks through the machine, bringing each thereof to a condition of rest at 15 each operating station, in turn, means for checking rearward movement of each blank when in proper position at each of said stations, means at the notching and edging stations for returning into engagement with 20 said checking means each blank which has been carried slightly beyond the same, and means at the forming and seam-compressing station for overcoming inertia of the blank being advanced thereto, both said last-men- 25 tioned means and said returning means being bodily withdrawable independently of each other and the latter independently of all other mechanisms, to render separately accessible both portions of the entire path of 30 travel of said blanks.

32. In a machine of the character described, the combination, with a series of mechanisms for successively forming can-bodies from flat sheet-metal blanks, said 35 series comprising preliminary notching and edging mechanisms and final forming and seam-compressing mechanisms, of means for advancing said blanks through the machine, bringing each thereof to a condition of rest 40 at each operating station, in turn, means for checking rearward movement of each blank when in proper position at each of said stations, a pivoted frame above said advancing means adapted to be swung vertically, means 45 carried by said frame and normally located at the notching and edging stations for yieldingly returning into engagement with said checking means each blank which has been carried slightly beyond the same, yield- 50 ing means at the forming and seam-compressing station for overcoming inertia of the blank being advanced thereto, said last-mentioned means being bodily withdrawable, whereby both portions of the entire 55 path of travel of said blanks may be rendered independently accessible.

33. In a machine of the character described, the combination, with a series of mechanisms for successively forming can-bodies from flat sheet-metal blanks, said 60 series comprising preliminary notching and edging mechanisms and final forming and seam-compressing mechanisms, of means intermittently operable to advance said 65 blanks step-by-step through the machine,

bringing each thereof to a condition of rest at each operating station, in turn, a series of yieldingly depressible stop-pawls for checking rearward movement of each blank after each advancing movement, and connected 70 means at each of the preliminary notching and edging stations and having common actuating means for returning into engagement with the positioning stop-pawls such blanks as have been carried slightly beyond 75 the same.

34. In a machine of the character described, the combination, with a series of mechanisms for successively forming can-bodies from flat sheet-metal blanks, said 80 series comprising preliminary notching and edging mechanisms and final forming and seam-compressing mechanisms, of means intermittently operable to advance said blanks step-by-step through the machine, bringing 85 each thereof to a condition of rest at each operating station, in turn, a series of yieldingly depressible stop-pawls for checking rearward movement of each blank after each advancing movement, and means at each of 90 the preliminary notching and edging stations for yieldingly returning into engagement with the positioning stop-pawls such blanks as are carried slightly beyond the same. 95

35. In a machine of the character described, the combination, with a series of mechanisms for successively forming can-bodies from flat sheet-metal blanks, said 100 series comprising preliminary notching and edging mechanisms and final forming and seam-compressing mechanisms, of means intermittently operable to advance said blanks step-by-step through the machine, bringing each thereof to a condition of rest at each operating station, in turn, a series of yieldingly depressible stop-pawls for checking rearward movement of each blank after each advancing movement, and horizontally reciprocating means at each of the preliminary 105 notching and edging stations for frictionally returning into engagement with the positioning stop-pawls such blanks as are carried slightly beyond the same. 110

36. In a machine of the character described, the combination, with a series of mechanisms for successively forming can-bodies from flat sheet-metal blanks, said 115 series comprising preliminary notching and edging mechanisms and final forming and seam-compressing mechanisms, of means for advancing said blanks through the machine, bringing each thereof to a condition of rest at each operating station, in turn, means for checking rearward movement of each blank 120 when in proper position at each of said stations, and means at certain of said stations for returning into engagement with said checking means each blank which has been carried slightly beyond the same, said last- 125 130

mentioned means comprising pivoted fingers the free ends of which are adapted to frictionally engage the upper face of each blank, in turn, and means for oscillating said 5 fingers.

37. In a machine of the character described, the combination, with a series of mechanisms for successively forming can-bodies from flat sheet-metal blanks, said 10 series comprising preliminary notching and edging mechanisms and final forming and seam-compressing mechanisms, of means for advancing said blanks through the machine, bringing each thereof to a condition of rest

15 at each operating station, in turn, means for checking rearward movement of each blank when in proper position at each of said stations, and means at certain of said stations for returning into engagement with said 20 checking means each blank which has been carried slightly beyond the same, said last-mentioned means being mounted on a frame which is withdrawable to render accessible the path of advancement of said blanks and 25 comprising pivoted fingers the free ends of which are adapted to frictionally engage the upper face of each blank, in turn, and means for oscillating said fingers.

38. In a machine of the character described, the combination, with a series of mechanisms for successively forming can-bodies from flat sheet-metal blanks, said series comprising preliminary notching and edging mechanisms and final forming and 35 seam-compressing mechanisms, of means for advancing said blanks through the machine, bringing each thereof to a condition of rest at each operating station, in turn, means for checking rearward movement of each blank 40 when in proper position at each of said stations, a pivoted frame above said advancing means adapted to be swung vertically, and means carried by said frame and normally located at certain of said stations for returning 45 into engagement with said checking means each blank which has been carried slightly beyond the same, said means comprising pivoted fingers the free ends of which are adapted to frictionally engage the upper 50 face of each blank, in turn, and means for oscillating said fingers.

39. In a machine of the character described, the combination, with a series of mechanisms for successively forming can-bodies from flat sheet-metal blanks, said series comprising preliminary notching and edging mechanisms and final forming and 55 seam-compressing mechanisms, of means for advancing said blanks through the machine, 60 bringing each thereof to a condition of rest at each operating station, in turn, means for checking rearward movement of each blank when in proper position at each of said stations, a pivoted frame above said advancing 65 means adapted to be swung vertically, and

means carried by said frame and normally located at the notching and edging stations for returning into engagement with said 70 checking means each blank which has been carried slightly beyond the same, said last-mentioned means comprising pivoted fingers the free ends of which are adapted to frictionally engage the upper face of each blank, in turn, and means for oscillating said 75 fingers.

40. In a machine of the character described, the combination, with a series of mechanisms for successively forming can-bodies from flat sheet-metal blanks, said series comprising preliminary notching and edging mechanisms and final forming and seam-compressing mechanisms, of means intermittently operable to advance said blanks step-by-step through the machine, bringing each thereof to a condition of rest at each operating station, in turn, a series of yieldingly deppressible stop-pawl for checking rearward movement of each blank after each advancing movement, and means at each of certain of said stations for yieldingly returning into engagement with the positioning stop-pawl each blank which has been carried slightly beyond the same, said means comprising pivoted fingers the free ends of which are adapted to frictionally engage the 95 upper face of each blank, in turn, and means for oscillating said fingers.

41. In a machine of the character described, the combination, with a series of mechanisms for successively forming can-bodies from flat sheet-metal blanks, said series comprising preliminary notching and edging mechanisms and final forming and seam-compressing mechanisms, of means intermittently operable to advance said blanks 100 step-by-step through the machine, bringing each thereof to a condition of rest at each operating station, in turn, a series of yieldingly deppressible stop-pawl for checking rearward movement of each blank after each advancing movement, a pivoted frame above said advancing means adapted to be swung vertically, and means carried by said frame and normally located at certain of said stations for yieldingly returning into engagement with the positioning stop-pawl each blank that has been carried slightly beyond the same, said last-mentioned means comprising pivoted fingers the free ends of which are adapted to frictionally engage the upper 115 face of each blank, in turn, and means for oscillating said fingers.

42. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine 120 125 130

bringing each thereof to a condition of rest at each operating station, in turn, said means comprising a pair of reciprocating blocks, a cross-bar between said blocks, and feed-bars secured to and actuated by said cross-bar, said feed-bars being provided with corresponding series of yieldingly depressible pawls, means for checking rearward movement of each blank when in proper position at each of said stations, and connected means at the preliminary notching and edging stations and having common actuating means for returning into engagement with said checking means such blanks as are carried slightly beyond the same. 43. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, said means comprising a pair of reciprocating blocks, a cross-bar between said blocks, and feed-bars secured to and actuated by said cross-bars, said feed-bars being provided with corresponding series of yieldingly depressible pawls, means for checking rearward movement of each blank when in proper position at each of said stations, a pivoted frame above said advancing means adapted to be swung vertically, and means carried by said frame and normally located at certain of said stations for returning into engagement with said checking means each blank which has been carried slightly beyond the same. 44. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, said means comprising a pair of reciprocating blocks, a cross-bar between said blocks, and feed-bars secured to and actuated by said cross-bar, said feed-bars being provided with corresponding series of yieldingly depressible pawls, a series of yieldingly depressible stop-pawls for checking rearward movement of each blank after advancing movement, and connected means at each of the preliminary notching and edging stations and having common actuating means for returning into engagement with the positioning stop-pawls such blanks as have been carried slightly beyond the same. 45. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, said means comprising a pair of reciprocating blocks, a cross-bar between said blocks, and feed-bars secured to and actuated by said cross-bar, said feed-bars being provided with corresponding series of yieldingly depressible pawls, means for checking rearward movement of each blank when in proper position at each of said stations, and connected means at the notching and edging stations for returning into engagement with said checking means each blank which has been carried slightly beyond the same, said last-mentioned means being mounted on a common supporting frame which is mounted for ready independent withdrawal to render accessible the path of advancement of said blanks. 46. In a machine of the character described, the combination, with a series of mechanisms for successively forming can-bodies from flat sheet-metal blanks, said series comprising preliminary notching and edging mechanisms and final forming and seam-compressing mechanisms, of means intermittently operable to advance said blanks step-by-step through the machine, bringing each thereof to a condition of rest at each operating station, in turn, said means comprising a pair of reciprocating blocks, a cross-bar between said blocks, and feed-bars secured to and actuated by said cross-bar, said feed-bars being provided with corresponding series of yieldingly depressible pawls, means for checking rearward movement of each blank when in proper position at each of said stations, and connected means at the notching and edging stations for returning into engagement with said checking means each blank which has been carried slightly beyond the same. 47. In a machine of the character described, the combination, with a series of mechanisms for successively forming can-bodies from flat sheet-metal blanks, said series comprising preliminary notching and edging mechanisms and final forming and seam-compressing mechanisms, of means for advancing said blanks through the machine, bringing each thereof to a condition of rest at each operating station, in turn, said means comprising a pair of reciprocating blocks, a cross-bar between said blocks, and feed-bars secured to and actuated by said cross-bar, said feed-bars being provided with corresponding series of yieldingly depressible pawls, means for checking rearward movement of each blank when in proper position at each of said stations, and connected means at the notching and edging stations for returning into engagement with said checking means each blank which has been carried slightly beyond the same, said last-mentioned means being mounted on a common supporting frame which is mounted for ready independent withdrawal to render accessible the path of advancement of said blanks.

- blocks, a cross-bar between said blocks, and feed-bars secured to and actuated by said cross-bar, said feed-bars being provided with corresponding series of yieldingly de-
5 pressible pawls, means for checking rear-
ward movement of each blank when in proper position at each of said stations, and means at certain of said stations for return-
ing into engagement with said checking
10 means each blank which has been carried slightly beyond the same, said last-mentioned means comprising pivoted fingers the free ends of which are adapted to friction-
ally engage the upper face of each blank, in
15 turn, and means for oscillating said fingers.
48. In a machine of the character de-
scribed, the combination, with a series of mechanisms for successively forming can-
bodies from flat sheet-metal blanks, said se-
20 ries comprising preliminary notching and edging mechanisms and final forming and seam-compressing mechanisms, of means for advancing said blanks through the machine, bringing each thereof to a condition of rest
25 at each operating station, in turn, said means comprising a pair of reciprocating blocks, a cross-bar between said blocks, and feed-bars secured to and actuated by said cross-bar, said feed-bars being provided with corre-
30 sponding series of yieldingly de-
pressible pawls, means for checking rearward movement of each blank when in proper position at each of said stations, and means at cer-
35 tain of said stations for returning into en-
gagement with said checking means each blank which has been carried slightly be-
yond the same, said last-mentioned means being mounted on a frame which is with-
drawable to render accessible the path of ad-
40 vancement of said blanks and comprising pivoted fingers the free ends of which are adapted to frictionally engage the upper face of each blank, in turn, and means for oscillating the fingers.
45 49. In a machine of the character de-
scribed, the combination, with a series of mechanisms for successively forming can-
bodies from flat sheet-metal blanks, said se-
50 ries comprising preliminary notching and edging mechanisms and final forming and seam-compressing mechanisms, of means for advancing said blanks through the machine, bringing each thereof to a condition of rest at each operating station, in turn, said means comprising a pair of reciprocating blocks, a cross-bar between said blocks, and feed-bars secured to and actuated by said cross-bar, said feed-bars being provided with corre-
55 sponding series of yieldingly de-
pressible pawls, means for checking rearward movement of each blank when in proper position at each of said stations, a pivoted frame above said advancing means adapted to be swung vertically, and means carried by said
60 frame and normally located at certain of said stations for returning into engagement with the position-
ing stop-pawls each blank which has been carried slightly beyond the same, said last-mentioned means comprising pivoted fingers the

frame and normally located at certain of 65 said stations for returning into engagement with said checking means each blank which has been carried slightly beyond the same, said means comprising pivoted fingers the free ends of which are adapted to friction-
ally engage the upper face of each blank, in turn, and means for oscillating said fin-
gers. 70

50. In a machine of the character de-
scribed, the combination, with a series of 75 mechanisms for successively forming can-
bodies from flat sheet-metal blanks, said se-
ries comprising preliminary notching and edging mechanisms and final forming and seam-compressing mechanisms, of means in-
termittently operable to advance said blanks 80 step-by-step through the machine, bringing each thereof to a condition of rest at each operating station, in turn, said means comprising a pair of reciprocating blocks, a 85 cross-bar between said blocks, and feed-bars secured to and actuated by said cross-bar, said feed-bars being provided with corre-
sponding series of yieldingly de-
pressible pawls, a series of yieldingly de-
pressible stop-
pawls for checking rearward movement of 90 each blank after each advancing movement, and means at each of certain of said stations for yieldingly returning into engagement with the positioning stop-pawls each blank 95 which has been carried slightly beyond the same, said means comprising pivoted fingers the free ends of which are adapted to frictionally engage the upper face of each blank, in turn, and means for oscillating said 100 fingers.

51. In a machine of the character de-
scribed, the combination, with a series of 105 mechanisms for successively forming can-
bodies from flat sheet-metal blanks, said se-
ries comprising preliminary notching and edging mechanisms and final forming and seam-compressing mechanisms, of means in-
termittently operable to advance said blanks 110 step-by-step through the machine, bringing each thereof to a condition of rest at each operating station, in turn, said means comprising a pair of reciprocating blocks, a cross-bar between said blocks, and feed-bars secured to and actuated by said cross-bar, 115 said feed-bars being provided with corre-
sponding series of yieldingly de-
pressible pawls, a series of yieldingly de-
pressible stop-
pawls for checking rearward movement of each blank after each advancing movement, 120 a pivoted frame above said advancing means adapted to be swung vertically, and means carried by said frame and normally located at certain of said stations for yieldingly re-
turning into engagement with the position-
ing stop-pawls each blank which has been car-
ried slightly beyond the same, said last-mentioned means comprising pivoted fingers the 125

free ends of which are adapted to frictionally engage the upper face of each blank, in turn, and means for oscillating said fingers.

52. In a device for notching opposite edges of a sheet-metal blank preliminary to forming the same into a can-body, the combination, with means for advancing said blank to and properly positioning the same in said device, of two opposite die-holders, notching dies mounted in each thereof, each of said die-holders being removably mounted at the upper end of a vertically reciprocating shaft and each shaft including a rack, laterally removable supports for said shafts, elongated pinions meshing with said racks, means for rocking said pinions to synchronously reciprocate said shafts, and means for positionally adjusting said shafts with reference to each other.

53. In a device for notching opposite edges of a sheet-metal blank preliminary to forming the same into a can-body, the combination, with means for advancing said blank to and properly positioning the same in said device, of two opposite die-holders, notching dies mounted in each thereof, each of said die-holders being removably mounted at the upper end of a vertically reciprocating shaft and each shaft including a rack, elongated pinions meshing with said racks, a shaft upon which said pinions are mounted, means for rocking said last-mentioned shaft, and means for positionally adjusting said first-mentioned shafts with reference to each other.

54. Mechanism for forming a can-body from a flat blank which consists of a mandrel, a pair of wings movable to embrace said mandrel and shape a blank therebetween, and means for advancing and retracting said wings, said means comprising a pivot-shaft, a pair of oscillating levers both pivoted on said shaft and extending to the same side of the machine, connecting-rods between said levers and said wings, respectively, and means actuated from a common driving element to oscillate said levers.

55. Mechanism for forming a can-body from a flat blank which consists of a mandrel, a pair of wings movable to embrace said mandrel and shape a blank therebetween, and means for advancing and retracting said wings, said means comprising a pivot-shaft, a pair of independently oscillating levers both pivoted on said shaft and extending to the same side of the machine, connecting-rods between said levers and said wings, respectively, and means actuated from a common driving element to oscillate said levers sequentially.

56. Mechanism for forming a can-body from a flat blank which consists of a mandrel, a pair of pivoted wings adapted to

be swung to embrace said mandrel and shape a blank therebetween, and means for swinging said wings, said means comprising a pivot-shaft, a pair of oscillating levers both pivoted on said shaft and extending to the same side of the machine, connecting-rods between said levers and said wings, respectively, and means actuated from a common driving element to oscillate said levers.

57. Mechanism for forming a can-body from a flat blank which consists of a mandrel, a pair of pivoted wings adapted to be swung to embrace said mandrel and shape a blank therebetween, and means for swinging said wings, said means comprising a pivot-shaft, a pair of independently oscillating levers both pivoted on said shaft and extending to the same side of the machine, connecting-rods between said levers and said wings, respectively, and means actuated from a common driving element to oscillate said levers sequentially.

58. Mechanism for forming a can-body from a flat blank which consists of a mandrel, a pair of wings movable to embrace said mandrel and shape a blank therebetween, and means for advancing and retracting said wings, said means comprising a pivot-shaft, a pair of oscillating levers both pivoted on said shaft and extending to the same side of the machine, connecting-rods between said levers and said wings, respectively, and yielding means actuated from a common driving element to oscillate said levers.

59. Mechanism for forming a can-body from a flat blank which consists of a mandrel, a pair of wings movable to embrace said mandrel and shape a blank therebetween, and means for advancing and retracting said wings, said means comprising a pivot-shaft, a pair of independently oscillating levers both pivoted on said shaft and extending to the same side of the machine, connecting-rods between said levers and said wings, respectively, and yielding means actuated from a common driving element to oscillate said levers sequentially.

60. Mechanism for forming a can-body from a flat blank which consists of a mandrel, a pair of pivoted wings adapted to be swung to embrace said mandrel and shape a blank therebetween, and means for swinging said wings, said means comprising a pivot-shaft, a pair of oscillating levers both pivoted on said shaft and extending to the same side of the machine, connecting-rods between said levers and said wings, respectively, and yielding means actuated from a common driving element to oscillate said levers.

61. Mechanism for forming a can-body from a flat blank which consists of a man-

drel, a pair of pivoted wings adapted to be swung to embrace said mandrel and shape a blank therebetween, and means for swinging said wings, said means comprising a pivot-shaft, a pair of independently oscillating levers both pivoted on said shaft and extending to the same side of the machine, connecting-rods between said levers and said wings, respectively, and yielding means actuated from a common driving element to oscillate said levers sequentially.

62. In a machine for forming can-bodies from flat sheet-metal blanks, the combination, with means for successively advancing said blanks step-by-step through the machine, of a series of mechanisms which comprises mechanism for notching opposite edges of each blank, mechanism for folding over said edges between the notches in opposite direction, mechanism for forming said blanks and bringing the oppositely folded edges thereof into interhooked relation and mechanism for compressing the interhooked portion into a tight seam, said forming mechanism comprising a mandrel and means adapted to shape and interhook a blank thereon, and said compressing mechanism comprising a die reciprocable to compress the interhooked portions of the formed blank against said mandrel, means for overcoming inertia of the blank being delivered to position relative to said mandrel for the forming operation, said means comprising a support, a brake-bar yieldingly carried by said support and adapted to frictionally engage the advancing blank and yieldingly retain the same in said position relative to said mandrel, means for automatically shifting said support to brace said mandrel during and against the forces of the compressing operation, and means operable at will for shifting said support whereby the same and said brake-bar may be withdrawn from and returned to operative positions.

63. In a machine for forming can-bodies from flat sheet-metal blanks, the combination, with means for successively advancing said blanks step-by-step through the machine, of a series of mechanisms which comprises mechanism for notching opposite edges of each blank, mechanism for folding over said edges between the notches in opposite directions, mechanism for forming said blanks and bringing the oppositely folded edges thereof into interhooked relation and mechanism for compressing the interhooked portion into a tight seam, said forming mechanism comprising a mandrel and means adapted to shape and interhook a blank thereon, and said compressing mechanism comprising a die reciprocable to compress the interhooked portions of the formed blank against said mandrel, means for overcoming inertia of the blank being delivered

to position relative to said mandrel for the forming operation, said means comprising an initially stationary reciprocable support, a brake-bar yieldingly carried by said support and adapted to frictionally engage the advancing blank and yieldingly retain the same in said position relative to said mandrel, means periodically operable automatically to reciprocate said support and brace said mandrel during and against the forces of the compressing operation, said last-mentioned means establishing substantial rigidity of structure during said compressing operation, and means operable at will for shifting said support whereby the same and said brake-bar may be withdrawn from and returned to operative positions.

64. In a machine for forming can-bodies from flat sheet-metal blanks, the combination, with means for successively advancing said blanks step-by-step through the machine, of a series of mechanisms which comprises mechanism for notching opposite edges of each blank, mechanism for folding over said edges between the notches in opposite directions, mechanism for forming said blanks and bringing the oppositely folded edges thereof into interhooked relation and mechanism for compressing the interhooked portion into a tight seam, said forming mechanism comprising a mandrel and means adapted to shape and interhook a blank thereon, and said compressing mechanism comprising a die reciprocable to compress the interhooked portions of the formed blank against said mandrel, and means periodically operable to brace said mandrel during and against the forces of the compressing operation, said last-mentioned means comprising a reciprocable support and automatically actuated and timed toggle-jointed levers for reciprocating the same whereby substantial rigidity of structure is established during said compressing operation.

65. In a machine for forming can-bodies from flat sheet-metal blanks, the combination, with means for successively advancing said blanks step-by-step through the machine, of a series of mechanisms which comprises mechanism for notching opposite edges of each blank, mechanism for folding over said edges between the notches in opposite directions, mechanism for forming said blanks and bringing the oppositely folded edges thereof into interhooked relation and mechanism for compressing the interhooked portion into a tight seam, said forming mechanism comprising a mandrel and means adapted to shape and interhook a blank thereon, and said compressing mechanism comprising a die reciprocable to compress the interhooked portions of the formed blank against said mandrel, means for overcoming inertia of the blank being delivered to position relative to said mandrel for the

- forming operation, said means comprising an initially stationary reciprocable support, a brake-bar yieldingly carried by said support and adapted to frictionally engage the advancing blank and yieldingly retain the same in position relative to said mandrel, and means periodically operable to reciprocate said support and brace said mandrel during and against the forces of the compressing operation, said last-mentioned means comprising automatically actuated and timed toggle-jointed levers whereby substantial rigidity of structure is established during said compressing operation.
66. In a machine for forming can-bodies from flat-sheet-metal blanks, the combination, with means for successively advancing said blanks step-by-step through the machine, of a series of mechanisms which comprises mechanism for notching opposite edges of each blank, mechanism for folding over said edges between the notches in opposite directions, mechanism for forming said blanks and bringing the oppositely folded edges thereof into interhooked relation and mechanism for compressing the interhooked portion into a tight seam, said forming mechanism comprising a mandrel and means adapted to shape and interhook a blank thereon, and said compressing mechanism comprising a die reciprocable to compress the interhooked portions of the formed blank against said mandrel, means for overcoming inertia of the blank being delivered to position relative to said mandrel for the forming operation, said means comprising an initially stationary reciprocable support, a brake-bar yieldingly carried by said support and adapted to frictionally engage the advancing blank and yieldingly retain the same in said position relative to said mandrel, means periodically operable automatically to reciprocate said support and brace said mandrel during and against the forces of the compressing operation, said last-mentioned means comprising toggle-jointed levers whereby substantial rigidity of structure is established during said compressing operation, and means operable at will for shifting said support whereby the same and said brake-bar may be withdrawn from and returned to operative positions.
67. In a machine of the character described, the combination, with a series of mechanisms for successively forming can-bodies from flat sheet-metal blanks, said
- series comprising preliminary notching and edging mechanisms and final forming mechanism, of means for advancing said blanks in succession step-by-step through said notching and edging mechanisms and into said forming mechanism, said means comprising a pair of reciprocating blocks, a cross-bar between said blocks, and feed-bars secured to and actuated by said cross-bar and provided with means for engaging said blanks, said forming mechanism including a mandrel around which each blank is formed, and a track-bar intermediate said feed-bars and reciprocated therewith, said bar being in length substantially coextensive with said feed-bars and the end thereof being provided with an extension projecting through and substantially forming a part of said mandrel and being provided with corresponding engaging means for continuing advancement of said blank after the forming operation.
68. In a machine of the character described, the combination, with a series of mechanisms for successively forming can-bodies from flat sheet-metal blanks, said series comprising preliminary notching and edging mechanisms and final forming mechanism, of means for advancing said blanks in succession step-by-step through said notching and edging mechanisms and into said forming mechanism, said means comprising a pair of reciprocating blocks, a cross-bar between said blocks, and feed-bars secured to and actuated by said cross-bar and provided with corresponding series of depressible pawls and said forming mechanism including a mandrel around which each blank is formed, and a track-bar secured to said cross-bar intermediate said feed-bars and reciprocated therewith, said bar being in length substantially coextensive with said feed-bars and the end thereof being provided with an extension projecting through and substantially forming a part of said mandrel and being provided with pawls similarly yieldingly depressible for continuing advancement of said blank after the forming operation.

In testimony of the foregoing, I have hereunto set my hand in the presence of two witnesses.

JULIUS BRENZINGER.
